UNITED STATES PATENT OFFICE.

FREDERICK L. JORGENSEN, OF CLEVELAND, OHIO.

AIR-TREATMENT APPARATUS FOR HAY FEVER, ETC.

Application filed August 1, 1925. Serial No. 47,441.

It is well known that hundreds of thousands of persons are annually afflicted with hay fever, and many thousands of persons suffer from the same disease in conjunction with asthma. Owing to the large number of people so afflicted, the problem of treatment for them by which to obtain relief has become increasingly important. The serum treatments which have now been given for a number of years are only effective in a relatively small number of cases.

As a general thing, physicians are agreed that the disease of hay fever arises from the peculiar susceptibility of the patient to certain pollens in the air, derived largely from plant life. Especially is the disease found to be due to the pollen of rag weed, timothy hay, golden rod and the like, the atmosphere over a large area of the country, and elsewhere, being heavily laden with the disease creating pollens of these different classes of plants.

As one who has suffered from asthma and hay fever over many years, I have reached the conclusion that in order to aid a person susceptible to hay fever from suffering with the disease, the air which he breathes must be treated so as to eliminate the possibility of action of pollens of the classes referred to upon the membranes of the nose and throat particularly. With the object therefore of separating from the air pollens or other foreign matter to which persons may be particularly susceptible, and which cause hay fever or rose fever or other vitality reducing diseases, I have devised a special apparatus adapted to be placed in a room in which the prospective patient may be located, whereby fresh air of sufficient quantity may be forcibly drawn into the room, submitted to treatment to filter therefrom the disease creating pollens or other foreign matter, the air thus treated being that which will be breathed by the person susceptible to the particular disease.

I contemplate that the room or compartment in which the person using my apparatus is located, may be his ordinary working office, his sleeping room, or it may be a special treatment room. The apparatus of my invention consists of an air suction means associated with a treatment means in the nature of a filtering device and said apparatus is made especially compact, simple and inexpensive so that it may be readily installed by persons of average means for use during the season or seasons of the year when they are afflicted

with hay fever or any general disease of the same general character created by pollen laden air.

For a full understanding of my invention and the merits thereof, reference is to be had to the following description and to the accompanying drawings, in which:

Figure 1 is a sectional view depicting a room or compartment of average size in which the apparatus of my invention is installed.

Figure 2 is a sectional view taken about on the line 2—2 of Figure 1 looking in the direction of the arrows.

Figure 3 is a front elevational view of the wall of the room having windows through one of which the air is drawn into the room and illustrating the suction device and air filtering means, in section.

Figure 4 is a perspective view of one of the air filtering members.

Describing my invention specifically and referring to the drawings, A denotes a room or compartment in which a hay fever patient, or person similarly afflicted, may work, sleep or play. This room is equipped with the usual windows 1 and as illustrated it is contemplated to keep these windows closed against the entrance directly into the room of pollen laden air. At one of the windows, preferably, though more than one of them might be so equipped, I provide a receiver B, consisting of a funnel like body held in place at the lower part of the window by the lower sash, in conjunction with the supporting piping hereinafter described. From the smaller end of this funnel like receiver B there leads an in-take pipe 2 which extends to the exhaust or suction fan 3 adapted to be operated by an electric motor 4 or any suitable power means. The air drawn into the pipe 2 by the suction device 3 is forced through a pipe 5 into the lower portion of a box or container 6 in which certain filtering means are located. The filtering means may be of different types but I preferably employ a series of V-shaped filters 7, seen best in Figure 4, as composed of the ends 7^a and the filtering cloths 7^b. The filtering cloths 7 may be made of cotton or other fabric material of suitable fineness to ensure that the pollen with which the air entering the box or container 6, is laden, from passing through the filtering cloths or member 7^b. After the air enters the lower end of the container 6 it passes into the wider lower ends of the filtering members 7 and

through said filtering members at the sides and upper ends. Thence the air passes through a secondary filtering means 8 preferably consisting of absorbent cotton diluted 5 with a moistening and antisepticizing substance such as glycerine or the like. This cotton 8 of the secondary filtering means is supported in place between two fine mesh screens 9 disposed horizontally across the upper end of the container 6.

At its top the container 6 is open and covered by a grate or fine mesh screen 10 through which the filtered and treated air drawn into the compartment passes in order to enter the 15 main portion of the compartment after being properly treated by means of my apparatus.

It is obvious that by reason of the arrangement of the several parts of the invention in compact disposition, these parts do not take 20 up much room and as their construction is relatively simple, the apparatus may be made at a comparatively low cost within the reach of the average person having need therefor. Moreover, said apparatus may be conveniently 25 installed in hospital rooms, or rooms located at any central stations of which the public may have notice, so that persons afflicted with diseases such as hay fever, asthma, rose fever, or the like, may enter and so far as 30 they remain, enjoy the relief of breathing purified air from which the pollen and dust have been completely removed.

The pipe 2 may be composed of telescopic sections for enabling ready adjustment of 35 the receiver B so it may be positioned in windows or other openings at different distances from the floor of the compartment in which the apparatus is arranged.

Having thus described my invention what I 40 claim as new and desire to cover by Letters Patent is:—

1. A portable hay fever apparatus comprising a funnel-like receiver having at its side, window frame and sash engaging means 45 for removably sustaining it in position in a

window, and having an opening positioned exterior to said window, a casing associated with said receiver, said casing enclosing a filtering element to and through which the air passes from said opening, said element 50 being composed of an antisepticized material and disposed to form pockets open to the air inlet, whereby to filter out pollen carried in by the air, and an impeller for drawing the air inwardly of the opening and through 55 said material.

2. A portable hay fever apparatus comprising a funnel-like receiver having at its side window frame and sash engaging means for removably sustaining it in position in a 60 window and having the entrance thereof disposed exteriorly to the window, air filtering means comprising a casing having at the bottom thereof a filtering element extending in a zig-zag or tortuous manner across the path 65 of the air introduced into said casing from the receiver aforesaid to form pockets through which the air is forced and a second antisepticized filtering element disposed above the first filtering element, and an impeller 70 for drawing the air through the receiver and impelling it through the filtering casing.

3. A portable hay fever apparatus comprising a funnel-shaped receiver having window frame and sash engaging means at the 75 sides thereof for removably positioning the receiver in a window with its entrance at the outside thereof, a filter device comprising a casing and enclosing a cloth filter through which the air is passed, a passage establishing communication between the receiver and said casing, an absorbent filtering element extending completely across the casing and adapted to hold an antiseptic liquid, an impeller located in the passage between the receiver and the casing, and motor driving means connected with said impeller.

In testimony whereof I affix my signature.

FREDERICK L. JORGENSEN.
